UNITED STATES PATENT OFFICE.

JOHN M. CROMLEY, OF LEWISBURG, PENNSYLVANIA.

RADIATOR TONGS.

Application filed April 7, 1921. Serial No. 459,343.

To all whom it may concern:

Be it known that I, JOHN M. CROMLEY, a citizen of the United States, residing at Lewisburg, in the county of Union and State of Pennsylvania, have invented certain new and useful Improvements in Radiator Tongs; and I do hereby declare the following to be a full, clear, and exact description of the invention, such as will enable others skilled in the art to which it appertains to make and use the same.

The present invention relates to devices or tongs adapted especially for carrying radiators, such as used in buildings for heating purposes, and aims to provide a novel and improved device of that kind, capable of adjustment for different sizes of radiators, and to different vertical positions thereon.

Another object is the provision of a device of that kind having means for engaging the end section of a radiator (one of the devices being used at each end), with handle-receiving members that can be adjusted to different positions for receiving handle rods extending either across the sides or ends of the radiator for convenience in carrying same, according to the size of the radiator and other conditions.

A further object is the provision of jaws to engage the opposite edges of the end section of a radiator, and novel means for connecting and mounting said jaws for adjustment toward and away from one another to accommodate radiator sections of different widths, and for holding said jaws against the radiator section.

A still further object is the provision of adjustable means to form a sling for the radiator to prevent the jaws slipping upwardly on the radiator when the device is applied.

It is also an object of the invention to provide a device of the nature indicated comprising a novel assemblage of the component elements, and which is also comparatively simple in construction, as well as being cheap and practical in use.

With the foregoing and other objects in view, which will be apparent as the description proceeds, the invention resides in the construction and arrangement of parts hereinafter described and claimed, it being understood that changes can be made within the scope of what is claimed, without departing from the spirit of the invention.

The invention is illustrated in the accompanying drawing, wherein:

Figure 1 is an elevation of one of the devices as applied to the end section of a radiator, with the handle rods extending across the sides of the radiator.

Fig. 2 is a plan view showing a pair of the devices on the opposite ends of a radiator, with the handle rods shown as extending across the sides of the radiator in full lines, and extending across the ends of the radiator in dotted lines.

Fig. 3 is a sectional detail through the joint of the pivoted bars of one of the devices.

Fig. 4 is a detail view of one of said bars showing the chain-engaging means thereof.

Each of the devices or tongs comprises a pair of jaws or plates 5 to bear against the outer side of the end section of a radiator or other similar object, and said jaws have hooks 6 at their opposite ends to engage across the edges of the radiator section, as seen in Fig. 2, for applying the device and holding the radiator or object.

The jaws 5 are connected for adjustment toward and away from one another, and, for this purpose, a pair of upwardly diverging bars 7 are employed, being pivotally connected at their lower ends by a bolt or rivet 8, and having their upper end portions overlapping and pivoted to the outer sides of the jaws 5, as at 9. Said bars can be swung apart for separating the jaws and will swing toward one another when the jaws are applied to the object. Furthermore, said jaws being pivoted to the bars can be swung about horizontal axes to enable the jaws and their hooks to properly engage the edges of the radiator section in the same position with the bars 7 in different angular positions.

Means is provided for holding the bars 7 against separation, whereby to clamp the jaws 7 against the object. Thus, a coiled retractile spring 10 has one end anchored, as at 11, to one bar 7, and a chain 12 is connected to the other end of the chain to detachably and adjustably engage the other bar 7, which is provided, for that purpose, with an angular slot 13 in its inner edge portion to receive the links of the chain 12 and forming a lug or hook 14 for the engagement of said links. When the jaws 5 are applied to the radiator section, the chain 12 can be pulled to stretch the spring 10

with the desired tension, and one link of the chain is then engaged over the lug 14, so that the bars 7 are connected to prevent the accidental separation thereof and to also 5 create a tendency for the bars to swing toward one another, thereby holding the jaws 5 in place under the spring tension.

Handle receiving members are carried by the jaws 5, and comprises the U-shaped loops 10 or clevises 15 having their ends hingedly or pivotally connected to the outer end portions of the jaws 5, by means of vertical hinge bolts or pins 16, permitting said handle receiving members 15 to be swung about 15 vertical axes to different positions. Thus, with the jaws 5 of the two devices applied to the opposite end sections of a radiator, as seen in Fig. 2, the members 15 can be swung outwardly, as seen in full lines in said Fig. 20 2, for the insertion of the handle rods 17 through the members to extend across the opposite sides of the radiator or across the edges of the sections thereof. By swinging the members 15 to the dotted line positions, 25 as seen in Fig. 2, to project beyond the ends of the radiator, the handle rods 17 can be inserted through said members to extend transversely across the ends of the radiator. In some cases, it is more convenient to position 30 the handles longitudinally across the opposite sides of the radiator to project beyond the ends thereof and in other cases it is desirable to position the handles across the ends of the radiators, which is especially 35 more convenient to enable four persons to lift and carry the radiator, whereas the position of the handles as shown in full lines in Fig. 2 is more suitable for two persons in carrying the object.

40 In order to prevent the jaws 5 from sliding upwardly on the object when the object is lifted, a sling chain 18 or other flexible element is provided, and has one end anchored to the rear end of the bolt or rivet 6 45 which pivotally connects the bars 7. Said chain can be passed around the end section of the radiator, and under the radiator, to form a sling, and the free terminal of the chain has the corresponding link thereof engaged with a hook 19 engaged with the forward terminal of the bolt or rivet 8. It is therefore an easy matter to pass the chain 50 under the radiator, after the jaws 5 are properly positioned and to engage the free terminal of the chain with the hook 19, so that the chain forms a sling for the radiator, to carry the radiator, assisted by the clamping of the jaws against the edges of the radiator section. When the object or radiator is lifted, 55 the weight of the object being imposed on the chain 18 and being transmitted by the bars 7 to the jaws 5 and handle rods 17, will create a tendency for the bars 7 to swing 60 toward one another, thereby pressing the jaws 5 tightly against the radiator section,

even without the assistance of the spring 10 and chain 12, although said spring and chain or other connecting means are essential to hold the device against accidental detachment.

70

Having thus described the invention, what is claimed as new is:—

1. A device of the character described comprising jaws for engaging an object to be lifted, and handle-receiving members pivoted to said jaws to be swung to different positions for receiving handles extending across the sides or ends of the object in different directions as may be desired.

2. A device of the character described comprising a pair of jaws having hooks to engage an object, and handle-receiving clevises hingedly connected with said jaws to swing to different positions for receiving handles extending across the sides or ends of the object in different directions.

3. A device of the character described comprising a pair of pivotally connected bars, jaws pivoted to said bars to move toward and away from one another to engage and disengage an object, and to be swung with respect to the bars to different positions for engaging the object.

4. A device of the character described comprising a pair of pivotally connected bars, jaws pivoted to said bars to move toward and away from one another and to be adjusted to different angular positions with respect to the bars, said jaws having hooks to engage a radiator section or other object.

5. A device of the character described comprising a pair of upwardly diverging pivotally connected bars, jaws pivotally connected with the upper end portions of said bars, and handle-receiving members carried by said jaws.

6. A device of the character described comprising a pair of upwardly diverging pivotally connected bars, jaws pivotally connected to said bars near the upper ends thereof to be adjusted for engaging the opposite edges of a radiator section or other object, and handle-receiving members pivotally connected to said jaws to swing about substantially vertical axes for receiving handles extending across the sides or end of the radiator or object.

7. A device of the character described comprising a pair of upwardly diverging pivotally connected bars, means carried by the upper end portions of the bars for engaging the opposite portions of the object, and means for connecting said bars under spring tension for holding them when swung toward one another to clamp the jaws against the object.

8. A device of the character described comprising a pair of upwardly diverging pivotally connected bars, means carried by the upper ends of said bars for engaging

130

the edges of a radiator section or other object and for receiving handles, a spring connected to one of said bars, and a chain connected to the spring, the other bar having means for the engagement of said chain for preventing the separation of the bars and keeping the chain under tension.

9. A device of the character described comprising a pair of bars having a pivot joint, jaws carried by the bars to engage a radiator section or other object, and a sling chain anchored to said joint, said joint having means for the engagement of said chain to form a sling.

15 10. A device of the character described comprising a pair of upwardly diverging bars, a pivot connecting said bars, means carried by the upper ends of said bars for engaging an object, means for connecting the bars to prevent the accidental separation thereof, a chain anchored at one end to said pivot, and a hook carried by the pivot for the engagement of the free terminal of said chain.

25 11. A device of the character described

having means for holding an object, and handle-receiving means for supporting the holding means adjustable to different positions for receiving handles extending across the sides or ends of the object in different 30 directions.

12. A device of the character described having means for holding an object, and handle-receiving means for supporting the holding means constructed and arranged 35 for receiving handles extending across the sides or ends of the object in different directions.

13. A device of the character described comprising means for holding an object including jaws to engage said object, and handle-receiving members for supporting the holding means constructed and arranged for receiving handles extending across the sides or ends of the object in different directions 40 45 as may be desired.

In testimony whereof I have signed my name to this specification.

JOHN M. CROMLEY.
